CLAIM

The ornamental design for a wash basin, as shown and described.

DESCRIPTION

FIG. 1 is a perspective view of a wash basin showing our design;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a top plan view thereof.

The broken lines in the drawings represent unclaimed portions of the wash basin and form no part thereof.
